G. BROWNING.
SAFETY RAZOR CASE.
FILED AUG. 12, 1921.

Indenter;
George Browning,

Witness:

Mr. W. H. G.

By Donald & Gordon
his Atty's.

UNITED STATES PATENT OFFICE.

GEORGE BROWNING, OF CHICAGO, ILLINOIS, ASSIGNOR TO LEE RAZOR MANUFACTURING COMPANY, OF CHICAGO, ILLINOIS, A CORPORATION OF DELAWARE.

SAFETY-RAZOR CASE.

Application filed August 12, 1921. Serial No. 431,684.

To all whom it may concern:

Be it known that I, GEORGE BROWNING, a subject of the King of Great Britain, residing at Chicago, in the county of Cook, 5 and the State of Illinois, have invented certain new and useful Improvements in Safety-Razor Cases, of which the following is a specification, reference being had to the accompanying drawings, forming a part 10 thereof.

The purpose of this invention is to provide a box or case for a safety razor including compartments for extra blades and arranged so that when the case is open, the 15 razor and blades are presented in convenient positions for removal. It consists of certain features and elements of construction and their combination hereinafter described and shown in the drawings, as indicated by the 20 claims.

In the drawings:

Figure 1 is a vertical medial section of a box or case embodying this invention showing a razor mounted therein with the handle partly in section to disclose the support 25 therefor.

Figure 2 is a front elevation of the box portion of the case with the razor removed therefrom, and with the cover cut off as indicated by the section line 2—2 on Figure 1.

Figure 3 is a horizontal section on a larger scale taken as indicated at line 3—3 on Figure 2.

Figure 4 is a detail section taken as indicated at line 4—4 on Figure 3.

Figure 5 is a side elevation of the case in closed position, with a small portion broken away to indicate the construction of the case.

Figure 6 is a detail section taken as indicated at line 6—6 on Figure 4.

The case as shown in the drawings is designed for manufacture in sheet metal drawn or stamped into shape, and consists essentially of a box portion including a back wall 1, and end wall, 2, rigidly and integrally associated, and a cover portion which includes the front wall, 3, and the other end wall, 4, rigidly and integrally associated. The cover member is hinged by a pivot, 5, to the edge 45 of the end wall, 2, and said wall, 2, carries an upstanding peg or post, 6, over which the hollow handle, 7, of the razor is telescoped for positioning the razor in the case.

In addition to the back wall, 1, and end 50 wall, 2, this portion of the case includes side

walls, 8, which are approximately triangular in shape, tapering in depth from their junction with the end wall, 2, down to a minimum depth near the opposite end of the back wall, 1. Thus, when the case lies open with 60 the handle, 7, of the razor engaged over the post, 6, the head portion, 9, of the razor is presented in a convenient position to be grasped and removed without interference from the side walls, 8, these being of minimum height in the vicinity of the head, 9. When the box is closed, its several sides are 65 rectangular in outline; therefore the side walls, 8, are supplemented by similar triangular side walls, 10, formed integrally with 70 the cover portion, 3, and end wall, 4.

In addition to enclosing the razor itself, the case is designed to carry trays, 11, for sharp and dull blades. Preferably these are each constructed of sheet metal folded 75 to form three sides of the tray, with their edges at one end slightly flared as shown at 12 in Figure 6, to interlock with the clinched edges, 13, of a cap or end plate, 14. At the opposite end, the folded sides 80 are formed with tangs, 15, engaging openings, 16, in a carrier plate, 17, which is hinged to the pivot, 5, and at the same time forms the opposite end wall for both of the trays, 11. When the case is closed 85 up, the open sides of the trays, 11, face the back wall, 1, and said wall serves as a closure for the trays. When the case is opened into position shown in Figure 1, one or both of the trays is manually engaged at the boss 90 or abutment struck up at 18, in the end wall, 14, and the assembly of the two trays on the carrier plate, 17, is tilted about the pivot, 5, into the position shown in dotted lines, in which the trays are upwardly open for convenience in removing blades therefrom. To facilitate such removal, the side walls may be cut away as at 19, to permit the blades, 20, to be directly grasped between the fingers. 95

As seen in Figure 3, the carrier plate, 17, is formed with a clearance notch, 21, extending around the post, 6, and preferably such notch is fitted closely to the post, 6, so that so long as the razor handle, 7, remains on 105 the post, it serves to lock the carrier plate against the bottom wall, 2; thus, in opening the case suddenly, there is no danger that the blade trays, 11, will swing over and dump the contents. 110

As seen in Figure 1, the post, 6, is bored at its lower end for securing by means of a dowel pin, 22, inserted through an aperture in the end wall, 2; and said end wall 5 is depressed at 23, forming a recess to accommodate the head, 24, of the said pin, 22, and this not only leaves the end wall substantially flat, so as to serve as a base for the box in open position, but it also forms 10 a boss interiorly projecting to meet the carrier plate, 17, and permitting clearance between the latter and the principal plane of the end wall, 2, which accommodates the tangs, 15, of the trays, 11. Referring to 15 Figure 3, it will be seen that the hinge connecting the two portions of the case comprises bent journal lugs, 25, on the end wall, 2, and similar lugs, 26, on the cover, 3, arranged laterally outside the lugs, 25. Between 20 the lugs, 25, the end of the plate, 17, is curled over at 27, to form a hinge for said plate; but at the middle, this part, 27, is cut away, forming a notch or opening, 28, through which the duplicate pivots, 5, may 25 be inserted. Said pivots may be tight enough to hold their positions by friction, and preferably their outer ends are concealed by the side walls, 10, of the cover member.

30 To limit the unfolding movement of the box sections, the end wall, 2, extends in a lip, 29, past the axis of the hinge, 5, so as to give support to the cover, 3, when it lies open as shown in Figure 1. This permits 35 the cover, 3, to act as a stop or rest for the trays, 11, when they are swung to open position as shown in dotted lines, and allows the box to be carried about in this position without danger of spilling the contents of 40 the trays. For holding the two sections in closed position a simple snap catch, 30, may be secured to the end wall, 4, with its curled free end extending to overhang the edge of the back wall when the parts are folded 45 together.

I claim:—

1. A box comprising two sections, one of which includes a back wall and one end wall rigidly associated, the other section including a cover and the opposite end wall rigidly associated with the cover portion of the one section hinged to the end wall of the other; and a tray pivotally attached to the box at the hinge axis arranged for closure of its open side by the back wall and adapted to swing away from said wall to give access to its contents.

2. A box comprising two sections, one of which includes a back wall and one end wall rigidly associated, the other section including a cover hinged to said end wall; a plate dimensioned to overly the end wall and pivotally attached to the box at the hinge axis and a tray secured at one of its 60 ends to said plate in position for closure

of its open side by the back wall and adapted to swing away from said wall about the hinge axis to give access to its contents.

3. In the combination defined in claim 2, said plate and tray being formed of sheet 70 metal and the plate constituting one end wall of the tray.

4. The combination of a tool or instrument having a hollow handle open at one end and a box therefor comprising two sections, one of which includes a back wall and one end wall rigidly associated, the other section including a cover hinged to said end wall, a post secured in said end wall extending approximately parallel to 75 the back wall to engage the hollow handle of the tool, a plate dimensioned to overly the end wall, and pivotally attached to the box at the hinge axis, a tray carried by said plate in position for closure of this open 80 side by the back wall, said plate having a notch closely fitting around the post to permit swinging the tray about said hinge axis, said handle of the tool being adapted to rest upon the plate adjacent the notch for 85 locking the tray in closed position while the tool remains upon the post.

5. In the combination defined in claim 4, said post projecting from the end of the box at the middle of its width and the plate 90 having two trays extending therefrom at opposite sides of the notch.

6. In the combination defined in claim 1, one of the box sections having a lip projecting past the hinge axis to lap under 100 the other section when they are unfolded for limiting the opening swing, whereby the cover in open position may serve as a rest for the tray when the latter is swung away from the bottom wall.

7. The combination of a box comprising two sections, one of which includes a back wall and one end wall rigidly associated, the other section including a cover and the opposite end wall rigidly associated with 105 the cover portion of the one section hinged to the end wall of the other, a tool or instrument having a hollow handle open at one end, a post projecting from said end wall substantially parallel to the back wall 110 to engage in said hollow handle of the tool, together with side walls for the section comprising the back and end walls, said side walls having a maximum depth adjacent the post but being cut down at the other end 115 of the box to give access to the tool, and complementary side walls associated with the cover section formed to connect with the side walls of the back section for completing the enclosure of the tool.

8. In the combination defined in claim 7, the back and cover of the box extending in substantially parallel planes when the box is closed, the side wall portions of both sections extending in coinciding planes and 125 130

their abutting edges running obliquely from points adjacent the hinge axis at one end of the box toward the back wall at the other end.

5 9. In the combination defined in claim 1, the end wall of the one section and the cover of the other section having two pairs of interlapped lugs adjacent their lateral margins bent into eyes to receive the hinge

pivot, side walls on one of said sections overlapping the openings of said lugs for concealing the hinge and the pivot being made in two sections inserted from between said pairs of lugs.

In testimony whereof, I have hereunto set 15 my hand at Chicago, Illinois this 9th day of August, 1921.

GEORGE BROWNING.
